US00D534551S

(12) United States Design Patent (10) Patent No.: US D534,551 S
(45) Date of Patent: * Jan. 2, 2007

(54) MORTAR MIXER

(75) Inventor: Gene Kushlan, Goldendale, WA (US)

(73) Assignee: Kushlan Products, Inc., Goldendale, WA (US)

() Term: 14 Years

(21) Appl. No.: 29/220,979

(22) Filed: Jan. 7, 2005

(51) LOC (8) Cl. 15-09

(52) U.S. Cl. D15/19

(58) Field of Classification Search D15/19,
D15/147; 366/47, 48, 57, 60, 63, 65, 181.3,
366/185, 193, 219, 228, 232, 241, 242

See application file for complete search history.

(74) Attorney, Agent, or Firm—Stoel Rives LLP

(57) CLAIM

The ornamental design for a mortar mixer, as shown and described.

DESCRIPTION

FIG. 1 is a front, left perspective view of a mortar mixer showing the new design;

FIG. 2 is a left-side perspective view thereof;

FIG. 3 is a top perspective view thereof;

FIG. 4 is a front perspective view thereof;

FIG. 5 is a right-side perspective view thereof;

FIG. 6 is a rear perspective view thereof; and,

FIG. 7 is a bottom perspective view thereof.

The broken lines showing in FIGS. 1–7 are for illustrative purposes only and form no part of the claimed design.

1 Claim, 7 Drawing Sheets
